US00D587269S

(12) **United States Design Patent**
Keeports et al.

(10) **Patent No.:** **US D587,269 S**
(b4) **Date of Patent:** **** Feb. 24, 2009**

(54) **RFID READER**

(75) Inventors: **Doug Keeports**, Murrysville, PA (US);
Keith Mayhood, Lower Burrell, PA (US)

(73) Assignee: **Vocollect, Inc.**, Pittsburgh, PA (US)

(**) Term: **14 Years**

(21) Appl. No.: **29/317,743**

(22) Filed: **May 6, 2008**

(51) **LOC (9) Cl.** **14-02**

(52) **U.S. Cl.** **D14/358**; D14/385; D14/188

(58) **Field of Classification Search** D14/356-370, D14/383-387, 402, 407-410, 432-435, 439, D14/448, 137, 138, 155, 188, 191, 299, 902; D13/107, 108, 123, 133, 154, 158, 162, 168, D13/184, 199; D3/201, 203.5, 203.6, 205, D3/218, 273-275, 302; D9/715, 414, 424, D9/426, 430-432, 499; 361/600, 622, 627-636, 361/724, 725, 679-687; 341/173, 176; 235/492

(57) **CLAIM**

The ornamental design for an RFID reader, as shown and described.

DESCRIPTION

FIG. 1 is a perspective view of the invention;

FIG. 2 is a front view of FIG. 1;

FIG. 3 is a bottom view of FIG. 1, with the top view being a mirror image;

FIG. 4 is a right side view of FIG. 1, showing the connector cord in phantom;

FIG. 5 is a right side view of FIG. 1;

FIG. 6 is a left side view of FIG. 1; and,

FIG. 7 is a rear view of FIG. 1.

Any elements shown in dash-dot broken lines form no part of the claimed invention in this application, and are instead included to show environmental aspects of the claimed invention.

1 Claim, 2 Drawing Sheets

FIG. 1

FIG. 2

FIG. 3

FIG. 4

FIG. 5

FIG. 6

FIG. 7
